UNITED STATES PATENT OFFICE.

CHARLES P. BEISEL, OF WILKESBARRE, PENNSYLVANIA.

DESIGN FOR A TRAY.

SPECIFICATION forming part of Design No. 34,920, dated August 13, 1901.

Application filed July 9, 1901. Serial No. 67,677. Term of patent 3½ years.

To all whom it may concern:

Be it known that I, CHARLES P. BEISEL, a citizen of the United States, residing at Wilkesbarre, in the county of Luzerne and State of Pennsylvania, have invented and produced a new and original Design for a Tray, of which the following is a specification.

This invention relates to a new and original design for a tray; and the essential features reside in an elongated body having an upstanding surrounding rim and panels at points intermediate of the said rim.

In the drawings, Figure 1 is a top plan view of a tray embodying the features of the design. Fig. 2 is a longitudinal vertical section of the same. Fig. 3 is a transverse vertical section on the line 3-3, Fig. 1.

The design is characterized by a body 1, having an upstanding surrounding rim 2 with end grip devices 3. At points intermediate 20 of the rim are upwardly-projecting panels 4.

Having thus described the invention, what is claimed as new is—

The design for a tray, as herein shown and described.

In testimony that I claim the foregoing as my own I have hereto affixed my signature in the presence of two witnesses.

CHAS. P. BEISEL.

Witnesses:

E. E. HOYLE,
FRANK S. APPLEMAN.
